MERCURY SWITCH RELAY

Charles H. Cartwright and Carl H. Larson, Elkhart, Ind., assignors to The Adlake Company, a corporation of Illinois

Application October 7, 1940, Serial No. 360,184

18 Claims. (Cl. 200—97)

This invention relates broadly to mercury switches, for certain features or parts of it can be used to advantage with almost any type of mercury switch, and is a continuation in part of our prior application Serial No. 202,003. But more specifically, the invention pertains to that type of mercury switch in which spaced electrodes, together with a quantity of mercury and a magnetically responsive displacer, are hermetically sealed within a glass envelope, after which the switch is associated with a coil which controls the movement of the displacer within the envelope to change the mercury level and thereby cause the electrical circuit between the spaced electrodes to be closed or opened according to the particular construction of the switch.

In general, the objects of the invention are to provide a time delay switch which, by slight changes in physical structure and/or apportionment of parts during fabrication, can be made to fulfill widely varying performance specifications; one which is relatively cheap to manufacture, particularly because it can be easily tested for its actual time delay characteristics before the parts are hermetically sealed within the switch envelope; and one which is reliable in performance over long periods of time.

These are but a few of the objects and advantages of the switch which will hereinafter be described, reference being had to the accompanying drawings, in which

Fig. 1 is a perspective view showing a novel and preferred mounting for the switch;

Fig. 2 is a vertical sectional view taken on the line 2—2 of Fig. 1, the switch, however, being shown in elevation;

Fig. 3 is a plan view of the switch with its mounting;

Fig. 4 is an enlarged vertical sectional view of a back contact switch embodying some of the principles of this invention, the switch parts being shown in their normal position of rest when the associated relay coil is deenergized;

Fig. 5 is a view showing the relationship of the switch parts at the instant when the displacer is raised by the associated coil;

Fig. 6 is a horizontal sectional view taken on the line 6—6 of Fig. 5;

Fig. 7 is a side elevational view of the time delay cup;

Fig. 8 is a vertical sectional view of a front contact switch embodying some of the principles of this invention, the switch parts being shown in the position which they take at the instant when

the associated coil is deenergized and the displacer rises, because of its buoyance, to the top of the switch envelope;

Fig. 9 illustrates the manner in which the time delay cup is instantly filled whenever the displacer is lowered by the action of the coil;

Fig. 10 is a horizontal sectional view taken on the line 10—10 of Fig. 8; and

Fig. 11 shows a modified form of the invention in which the switch parts are constructed and arranged so that there is a relatively short time interval when the circuit through the switch is being closed and a relatively long time interval when the circuit through the switch is being opened.

Certain preferred forms of the invention have been chosen for illustration and description, in compliance with Section 4888 of the Revised Statutes, and the appended claims should be construed as broadly as the prior art will permit.

The switch mounting

The switch mounting shown in Figs. 1 to 3 is a simple and inexpensive construction which not only provides an efficient iron circuit for the magnetic flux, but also affords physical protection for the switch.

The mounting for the switch, generally designated 20, comprises an L-shaped plate 21 connecting top and bottom pole plates 22 and 23, respectively, the latter having a downwardly extending flange 24 by which the relay may be mounted on the wall by screws 25. The switch-operating coil 26 is telescoped over the switch 20 and over top and bottom pole sleeves 27 and 28, which are rigidly secured to the top and bottom pole plates 22, 23, respectively. The plates 22 and 23 are removably secured to the L-shaped plate 21 by screws 29, so that the switch may be readily inserted in the coil 26 and assembled with the associated iron circuit, and when so assembled the bottom of the switch is supported on the horizontal flange 30 of the plate 21, and the top of the switch is slightly below the top of the sleeve 27, so that it is amply protected from accidental blows.

Preferably the iron circuit is made of cold rolled steel, annealed, or any high grade soft iron.

Back contact switch (quick make, slow break) 50

The switch shown in Figs. 4-7 inclusive is a quick make, slow break, back contact switch, comprising a switch envelope 31 (preferably of 733A glass), through the base of which molybde-

15

15

30

35

40

45

50

55

num electrodes 32, 33, are pinch-sealed. The electrode 32 is surrounded by a glass insulating sleeve 34 to a point 35, where it is fused with a short sleeve 36, of refractory tubing, preferably made of ceramic material, such as Alundum RA84 or RA360, inasmuch as this material is readily fusible with Corning 733A glass. The end of the electrode 32 is bare, leaving a contact portion 37 which extends a substantial distance above the top of the sleeve 36, and is adapted to be intermittently placed in electrical contact with the mercury fill 44 of the switch.

The electrode 33 may, if desired, be surrounded by a glass sleeve for a portion of its length, but a substantial part of the electrode is exposed to contact with the mercury fill below the time delay cup, generally designated 38, forming a contact 39. The bared end of the electrode 33 extends into the time delay cup 38, forming a contact 40 which is constantly immersed in the mercury within the cup.

The time delay cup 38 consists of an elongated ceramic tube 42 (preferably made from Alundum RA84 or RA360), the base of which is fused to a glass enlargement or bead 43 associated with the electrodes 32, 33. The cup 38 is telescoped over both of the contacts 37, 40, and at some point below the contact 37, the side wall of the cup is reduced in thickness, as indicated at 44, by means of a grinding wheel or file, and through this thinned portion of the cup wall a small mercury passage 45 is provided which constitutes the timing element for the switch.

The mercury fill is adapted to be raised and lowered between high and low levels by means of a magnetically responsive displacer 46, the top of which is slightly above the lower pole sleeve 28 when the coil 26 is deenergized. Springs 47, 48, are secured to the top and bottom, respectively, of the displacer 46 to cushion the movement of the displacer within the envelope, and to clamp guide washers 49 in place on the displacer. The upper portion of the displacer is enlarged to provide greater mass for the displacer, but the interior of the displacer is in free communication with the space on the outside of the displacer through an opening 50, so that the gas fill of the envelope, which preferably includes both helium and hydrogen, can readily pass through the top of the displacer without impedance.

The switch parts in Fig. 4 are shown in the position which they take when the coil 26 is deenergized, and it should be noted that the level of the mercury, when the displacer is in its lower position (the high mercury level), is above the lower edge 51 of the cup 38. The upper margin of the cup is inclined, so that when mercury is displaced to close the circuit through the electrodes 32 and 33, the mercury can enter the cup on the side adjacent to the low point 51, while the gas in the cup will escape along the opposite side of the cup. Obviously when the cup 38 is filled with mercury the circuit through the contacts 37 and 40 is closed.

When the displacer 46 is raised to the position shown in Fig. 5, the mercury level on the outside of the cup 38 falls immediately to a position slightly above the passage 45, but the column of mercury within the cup 38 recedes gradually as mercury passes slowly through the restricted passageway 45 into the main body of mercury. As soon as the mercury level within 75 the cup falls below the top of the ceramic sleeve

36, the circuit through the contacts 37 and 40 is broken.

Subsequent deenergization of the coil 26 will result in the displacer falling to the position in which it is shown in Fig. 4, and the immediate displacement of mercury by the displacer will cause the cup 38 to become instantaneously flooded with mercury, with the result that the circuit through the electrodes 32 and 33 is made within a few hundredths of a second after the 10 coil is deenergized.

Front contact switch (quick make, slow break)

The front contact switch shown in Figs. 8-10 inclusive differs but slightly from the back contact switch of Figs. 4-7 inclusive, the principal difference being that the time delay cup 39 of the front contact switch is positioned somewhat higher within the envelope and the displacer 52 is of lighter construction. To the extent that the 20 switch parts are the same, or substantially alike, no description is necessary, and these parts are indicated by like numbers on the drawings.

The displacer 52 comprises an outer sleeve 53 of magnetic material, interiorly fitted with a 25 refractory sleeve 54, preferably of glass or ceramic material, which projects from both ends of the sleeve 53. The two sleeves are held in desired relative position by the top and bottom springs 47, 48, which are tightly fitted over the projecting ends of the sleeve 54, as clearly shown in the drawings.

The air gap 55 between the top and bottom pole pieces 27, 28, is somewhat lower than the air gap in the back contact switch of Figs. 4-7 35 inclusive, and when the coil 26 is energized the displacer is pulled down to the bottom of the switch envelope, as shown in Fig. 9, to immediately flood the cup 39 with mercury and substantially instantaneously establish the electrical 40 circuit between the electrodes 32 and 33. Upon deenergization of the coil 26 the displacer rises by its buoyancy to the position in which it is shown in Fig. 8, and the mercury level outside of the cup 39 immediately drops to the level in 45 which it is shown in Fig. 8. As the mercury gradually escapes from the cup 39 through the opening 45, the mercury level within the cup 39 recedes until it falls below the edge 56 of a ceramic cup 57 associated with the contact 37, and as the mercury passes the edge 56 the circuit through the contacts 37 and 40 is broken. The time which it takes for the mercury to recede from the top of the time delay cup 39 to the edge 56 of the electrode cup 57 represents the 55 time delay factor of the switch. When the mercury has leveled off with the displacer in raised position it is at its low level, as indicated by the line 58.

Front or back contact switch (slow make and slow break)

It is apparent that by very slight modifications the back and front contact switches shown in Figs. 4-10 inclusive can be easily 65 changed into slow make, slow break switches, i. e., switches in which the time delay action of the restricted mercury passage 45 is utilized on making the circuit through the electrodes, 70 as well as when breaking that circuit. This may be accomplished merely by using a smaller quantity of mercury in the switch, so that when the displacer 46 of the back contact switch and the displacer 52 of the front contact switch are 75 lowered to the positions in which they are shown

in Figs. 4 and 9, respectively, the mercury fill fails to rise above the edge 51 of the cup 39, although it must rise above the top of the sleeve 36 (Fig. 4) and above the edge 56 of the electrode cup 57 (Fig. 8). By this arrangement the only way mercury is permitted to enter the cup 39 is through the restricted opening 45, and the distance between the low level of the mercury (i. e., the level of the mercury when the displacer is in its raised position and the mercury is at rest, as indicated by the lines 58 in Figs. 5 and 8), and the lowermost effective point on the contact 37 (the top of the sleeve 36 in Fig. 4, and the edge 56 of the cup 57 in Fig. 8), determines the time delay characteristics of the switch for the making of the circuit.

Since the high mercury level, indicated by the line 59 in Figs. 5 and 8, in a slow make, slow break switch of this type (as well as the slightly higher mercury level which is reached at the instant the displacer is lowered) is above the top of the sleeve 36 and the edge 56 of the electrode cup 57, the breaking of the circuit through the electrodes will be delayed by the retarded drop of the mercury column within the time delay cup 39. In some cases it may be desirable to increase the height of the cup 39 in order to make certain that mercury will not overflow the top of the cup and destroy the timing action of the restricted mercury passage 45 when closing the circuit between the electrodes 32 and 33.

Front or back contact switch with retarded make and slow break

35 In Fig. 11 there is shown a switch which has a relatively short time delay when the circuit is being closed, and a relatively long time delay when the circuit is being opened. By way of example, the switch may have a six second time delay when making the circuit, and a three minute time delay when breaking the circuit, and this particular relationship of time delays is extremely difficult to obtain in switches of this type.

45 The switch shown in Fig. 11 is of the front contact type, but it is obvious that the principles of the switch could easily be incorporated in a back contact switch. To the extent that the switch corresponds with the front contact switch in Figs. 8-10 inclusive, the description will not be repeated, and like reference characters are used on the drawings. The principal difference between the two switches is that a gas impervious thimble 60, preferably of glass, is sealed to the electrodes 32, 33, in place of the cup 39, and the thimble is provided in its top wall with a mercury valve, generally designated 61, comprising a porous seat 62, preferably of coarse ceramic material, such as Alundum, grade RA98, and a telescoping sleeve 63 of relatively dense ceramic material, such as Alundum, grade RA84. The sleeve 63 and seat 62 are fused into the top wall of the thimble to form a mercury valve cup, and the parts of the switch are so proportioned that when the displacer 52 is lowered the mercury rises above the top of the thimble 60 a sufficient distance to make certain that a quantity of mercury 64 is in the valve cup 61. The lower portion of the thimble 60 is provided with a restricted mercury passage 45, which retards the flow of mercury between the interior and exterior of the thimble.

70 When the switch parts are in the position in which they are shown in Fig. 11, with the mercury at its low level, the circuit through the

electrodes is open. Upon lowering the displacer 52 by the action of the coil 26 (or by deenergizing the coil in the case of a back contact switch), the mercury level on the outside of the thimble immediately rises to a level indicated by the line 55, which preferably is above the edge 66 of the sleeve 63 to insure that the mercury valve cup 61 will be filled with mercury. The mercury within the thimble 60 gradually rises as mercury is permitted to flow into the thimble 10 through the restricted passageway 45, and as soon as the level reaches the edge 56 of the cup 57 the circuit through the electrodes 32, 33, will be closed. The time for the mercury to reach this height depends, of course, upon the size of 15 the opening 45, the diameter of the thimble 60, and certain other factors. The gas entrapped within the thimble 60 does not in any way retard the movement of mercury to circuit closing position, because the seat 62 is sufficiently porous 20 to readily pass the gas through the seat and through the mercury globule 64 in the cup 63 without creating any substantial back pressure.

When the mercury in the switch has leveled off to its normal high level 67, due to the displacement of the gas in the thimble 60 with mercury, the thimble 60 is completely filled with mercury and subsequent deenergization of the coil, which causes the displacer 52 to rise to its uppermost position, as shown in Figs. 8 and 11, 30 has the result of lowering the outside mercury level to the position indicated by the line 68; but the mercury within the thimble 60 is restrained in its downward movement by the slow passage of gas through the dense porous sleeve 35 63 and seat 62, the mercury 64 in the valve 61 preventing gas from passing through the seat 62 into the thimble 60 without first traversing the dense time delay sleeve 63. The time that it takes for the mercury to fall from the top of 40 the mercury chamber in the thimble 60 to the edge 56 of the electrode cup 57 constitutes the time delay interval which characterizes the breaking of the circuit, and this interval is dependent for its value on the density of the sleeve 63, the 45 diameter and thickness of the walls of that sleeve, the diameter of the thimble 60, the difference in height between the top of the mercury chamber in the thimble 60 and the edge 56 of the mercury cup, and various other factors. It is not 50 difficult with this arrangement to obtain time delays of several minutes on the breaking of the circuit through the electrodes of the switch.

It should be noted that the restricted mercury passage 45 does not interfere with the timing action of the sleeve 63, because the gas time delay element is much slower in its action than the mercury leakage element.

In switches of the type described it is important that at no time during the cycle of the 60 switch a substantial current be required to pass through the mercury metering orifice 45, as it has been found that even the momentary passage of substantial currents, if repeated for a sufficient number of times, tends to deleteriously affect the walls of the orifice and so destroy the accurate timing action of the switch.

We avoid this undesirable action, in some instances, by placing the contacts of both electrodes within the time delay cup. Referring to Fig. 11, 70 it may be seen that in this type of switch the circuit through the electrodes cannot be completed until the mercury within the time delay body has risen above the level of the electrode cup 56, and that the circuit, when completed, 75

includes the contact 48, the mercury within the cup, and the contact 37, totally excluding the restricted mercury passage 45.

In other types of switches, however, such as 5 the type illustrated in Figs. 8 and 9, where the top of the time delay cup is open, there is an instant during the cycle of the switch when the circuit between the electrodes could be completed through the mercury metering orifice 45, 10 if it were not for the provision of the contact 38 without the cup. Assuming that the electrode 33 is completely insulated, and that no contact 38 without the cup is provided, it may be seen that when the circuit through the electrodes is 15 open and the coil is suddenly energized, the mercury fill will be raised by the displacer 52 and will flow over the edge 51 of the time delay cup 39. During this portion of the cycle the mercury may come in contact with the contact 37 20 or the mercury within the electrode cup 31, thereby completing a circuit through the contact 48, the mercury metering orifice 45, the mercury fill and the contact 31.

However, when the electrode 33 is provided 25 with a contact 38, without the time delay cup 39 (as shown in the drawings), the mercury spilling over the edge 51 of the cup 39 will complete the circuit primarily between the contacts 37 and 38, as this is the circuit of least resistance. 30

It is, of course, obvious that a certain amount of current will pass from the contact 48 through the mercury metering orifice 45 to the contact 37, but this current will be negligible, for, due to the small diameter of the orifice 45, the resistance in the circuit between contacts 48 and 37 will be much greater than the resistance in the circuit between contacts 37 and 38, and the current flowing in each of the circuits will, therefore, be inversely proportional to the resistances in the circuits. Actually the current flowing through the orifice 45 will be so small that it cannot damage the walls of the orifice. Once 45 the time delay cup 39 is filled the normal path of the current through the electrodes will be between the contacts 48 and 37, which does not, of course, include the restricted mercury passage 45.

It may be seen, therefore, that in a switch of 50 the type illustrated in Fig. 11 it is not necessary to provide a continuously exposed heel contact 38, but in switches of the type illustrated in Figs. 8 and 9 the provision of such a contact is highly desirable as it greatly increases the accurate life 55 of the time delay element.

Summary of advantages

The switch structures which have been described have certain inherent advantages, and 60 these will be mentioned briefly.

1. It is obvious that the time intervals for making and breaking the electrical circuits can be varied between wide limits by properly choosing appropriate dimensions for the time delay cup 39 and the mercury orifice 45, and by properly 65 positioning the intermittently immersed contact within the cup 39.

2. Since the functioning of the time delay element is not dependent upon gas densities (with 70 the exception of the modified form shown in Fig. 11), the switch can be readily tested during fabrication for its actual time delay values with the assurance that the same time delay values will obtain when the switch is hermetically sealed off 75 at the top, as indicated at 88. For example, it

is known that a .027 drill will give a six second time delay for a switch of given dimensions. Much time and labor is saved in this way and the switch can be produced with a corresponding saving in cost. 5

3. Making the time delay cup 39 of ceramic material and placing the mercury orifice below the low mercury level in a relatively thin wall of the cup greatly increases the accuracy of the time delay functions of the switch, since the short passage through the side wall of the cup is too small to house a bubble which might interfere with the smooth flow of mercury between the interior and exterior of the cup, and any bubble which finds its way into the opening will immediately disappear because the pressure of mercury on both sides of the opening forces the gas through the surrounding porous wall of the ceramic cup 39. 10 15

4. Although it is not essential in all cases to have the opening 45 below the low mercury level, 20 for extreme accuracy it is preferred because the error introduced by the erratic effect of surface tension is avoided.

5. The extended contact 37 in Figs. 4-10 inclusive serves a dual function. Although it is 25 impossible to determine for a certainty that the exceptionally quick and clean closing of the circuit through the electrodes 32 and 33 (clean in the sense that oscillograph records show that there is no chatter when the circuit is closed) is 30 obtained in a particular way, it seemed probable that the explanation for this desirable action is that the mercury, in spilling over the edge of the cup 42, first strikes the contact 37, thereby immediately closing the circuit through the electrodes, and the continued rush of mercury into the cup prevents any separation of the mercury column from the contact which could produce a chatter. In addition the extended contact 37 decreases the contact resistance of the switch 40 when the circuit is closed. 35 40

6. It has been found by extensive tests that the time for closing the circuit is decreased and made more uniform when the top of the cup 39 is slanted, as shown in the drawings, presumably 45 because the mercury tends to enter the cup on the low side and the gas tends to escape from the high side. 50

7. By having contacts 37 and 48 within the cup 39, and contact 38 without the cup, the direct 55 path of the electrical circuit between the electrodes 32 and 33 excludes the restricted mercury orifice 45, thus imparting a higher current carrying capacity and greatly increasing the accurate life of the switch. The increased contact area obtained through the use of contacts 38 and 48 on a heel electrode cooperates with the extended contact 37 to further decrease the contact resistance of the switch. 60 65

8. A switch of the type disclosed can be used very successfully on structures which are subjected to much jostling or vibration, as, for example, automobiles, buses, railway cars, and the like. 65

We claim as our invention:

1. In a mercury switch, a switch envelope, a mercury fill, electrodes projecting into the envelope, one of the electrodes having a contact adapted to be intermittently placed in electrical contact with the mercury fill, a cup telescoped over said contact and being provided with a restricted mercury passage below the level of said contact, and a displacer telescoped over the cup for raising the mercury fill within the cup to a point above the contact, said cup having a gas 70 75 75

pervious wall in the region of the restricted mercury passage and the passage being normally below the mercury fill.

2. In a mercury switch, a switch envelope, a mercury fill, electrodes projecting into the envelope, one of the electrodes having a contact adapted to be intermittently placed in electrical contact with the mercury fill, a cup telescoped over said contact and being provided with a restricted mercury passage below the level of said contact, and a displacer telescoped over the cup for raising the mercury fill within the cup to a point above the contact, one edge of said cup being cut away to facilitate filling of the cup with mercury.

3. In a mercury switch, a switch envelope, a mercury fill, electrodes projecting into the envelope, one of the electrodes having a contact adapted to be intermittently placed in electrical contact with the mercury fill, a cup telescoped over said contact and being provided with a restricted mercury passage below the level of said contact, and a displacer telescoped over the cup for raising the mercury fill within the cup to a point above the contact, the other of said spaced electrodes being positioned so that the mercury column passing through the restricted mercury passage is never required to conduct more than a small fraction of the entire current.

4. In a mercury switch, a switch envelope, a mercury fill, means for shifting the fill between high and low levels including a tubular displacer open at the lower end to the free passage of mercury, spaced electrodes in the envelope, one of which is adapted to be intermittently placed in contact with the mercury fill, a cup-shaped body immovably mounted within the envelope enclosing said one electrode and having its open end above the low mercury level, and a restricted mercury orifice below the low mercury level at all times submerged in the mercury fill, said orifice timing the flow of mercury as it passes from the cup-shaped body to the main body of the mercury fill as the latter is shifted from high level to low level.

5. In a mercury switch, a switch envelope, a mercury fill, means for shifting the fill between high and low levels, spaced electrodes in the envelope one of which projects upwardly through the mercury fill and is insulated from the mercury fill for a portion of its length leaving an exposed contact, a cup-shaped body supported at least in part by said one electrode and enclosing the contact, said body having a restricted orifice below the low level of the mercury whereby the orifice is at all times submerged in the mercury fill, said orifice serving to time the flow of mercury from the body when the mercury is shifted from high level to low level by said mercury shifting means.

6. In a mercury switch, a switch envelope, a mercury fill, means for shifting the fill between high and low levels, spaced electrodes in the envelope one of which projects upwardly through the mercury fill and is insulated from the mercury fill for a portion of its length leaving an exposed contact, the other electrode also having an exposed contact, a cup-shaped body supported at least in part by said one electrode and enclosing both contacts, said body having a restricted orifice below the low level of the mercury whereby the orifice is at all times submerged in the mercury fill, said orifice serving to time the flow of mercury from the body when the mercury fill is shifted from high level to low level by said mercury shifting means.

7. In a mercury switch, a switch envelope, a mercury fill, means for shifting the fill between high and low levels, spaced electrodes in the envelope, one of which is adapted to be intermittently placed in contact with the fill, said one electrode projecting upwardly through the fill and being insulated for a portion of its length leaving an exposed contact, a cup-shaped body of insulating material mounted on said one electrode and enclosing the contact portion thereof, said cup-shaped body having its open top positioned above the contact and having a restricted orifice below the contact for restraining the flow of mercury from the cup-shaped body to the main body of the mercury fill as the mercury fill is shifted from high level to low level.

8. In a mercury switch, a switch envelope, a mercury fill, means for shifting the fill between high and low levels, spaced electrodes in the envelope, one of which is adapted to be intermittently placed in contact with the fill, said one electrode projecting upwardly through the fill and being insulated for a portion of its length leaving an exposed contact, the other electrode also having an exposed contact, a cup-shaped body of insulating material mounted on said one electrode and enclosing both contacts, said cup-shaped body having its open top positioned above the contact which is intermittently placed in electrical connection with the main body of the mercury fill and having a restricted orifice below said intermittently immersed contact for timing the flow of mercury from the cup-shaped body as the mercury fill is shifted from high level to low level.

9. In a mercury switch, a switch envelope, a mercury fill, means for shifting the fill between high and low levels including a tubular displacer open at its lower end to the free passage of mercury, spaced electrodes in the envelope one of which is adapted to be intermittently placed in contact with the mercury fill, a cup-shaped body immovably mounted within the envelope enclosing said one electrode, and having its open end above the low mercury level, and a restricted mercury orifice below the low mercury level at all times submerged in the mercury fill, said cup-shaped body having a relatively thin wall in the region of the restricted mercury orifice, the orifice timing the flow of mercury as it passes from the cup-shaped body into the main body of the mercury fill as the latter is shifted from high to low level.

10. In a mercury switch, a switch envelope, a mercury fill, electrodes within the envelope having contacts at different heights, a ceramic cup rigidly telescoped over two of the contacts including a mercury metering orifice below the low level of the mercury fill to time the passage of mercury out of the cup, and means to raise the mercury fill above the level of both contacts.

11. In a mercury switch, a switch envelope, a mercury fill, spaced electrodes extending upwardly through the fill and insulated therefrom by sleeves defining contacts at different heights, one of said contacts being adapted to be intermittently immersed in the mercury fill, a cup-shaped body supported at least in part by one of said sleeves and enclosing two of the contacts, said body having a restricted mercury metering orifice in its wall below the upper contact and at all times submerged in the mercury fill, and means for shifting the mercury fill to above both contacts, said cup-shaped body also enclosing a portion of one of said insulating sleeves.

12. In a mercury switch, a switch envelope, a

mercury fill, electrodes having contacts within the envelope, one of the electrodes having a contact adapted to be intermittently placed in electrical contact with the mercury fill, a time delay body rigidly telescoped over the contact and having a restricted mercury passage, and means for shifting the level of the mercury fill, the other of said electrodes having a contact so positioned that the mercury column in the restricted mercury passage is at no time required to conduct more than a fraction of the entire current flowing through the electrodes and the mercury fill.

13. In a mercury switch, a switch envelope, a mercury fill, electrodes having contacts within the envelope, one of the electrodes having a contact adapted to be intermittently placed in electrical contact with the mercury fill, a ceramic cup having a restricted mercury passage in its side wall rigidly telescoped over said contact, and a magnetically responsive displacer for shifting the level of the mercury fill, the other of said electrodes having contacts so positioned that the mercury column in the restricted mercury passage is at no time required to conduct more than a fraction of the entire current flowing through the electrodes and the mercury fill.

14. In a mercury switch, a switch envelope, a mercury fill, electrodes having contacts within the envelope, a cup telescoped over at least part of said electrodes, said cup being open at its upper end and having a restricted mercury passage at all times immersed in the mercury fill, and means for shifting the level of the mercury fill, said electrodes having contacts at different heights within the cup, and one of said electrodes also having a contact without the cup whereby the mercury column in the restricted mercury passage is at no time required to conduct more than a fraction of the entire current flowing through the electrodes and the mercury fill.

15. In a mercury switch, a switch envelope, a mercury fill, means for shifting the fill between high and low levels including a tubular displacer open at its lower end to the free passage of mercury, spaced electrodes in the en-

velope, one of which is adapted to be intermittently placed in contact with the mercury fill, a cup-shaped body immovably mounted within the envelope enclosing at least a portion of said one electrode and having its open end above the high mercury level, and a restricted mercury orifice below the low mercury level at all times submerged in the mercury fill, said orifice timing the flow of mercury as it passes into and out of the cup-shaped body responsive to changes in the level of the mercury fill.

16. In a mercury switch, a switch envelope, a mercury fill, means for shifting the level of the mercury fill, electrodes having contacts at different heights within the envelope, a cup associated with said contacts having a restricted mercury orifice below the level of the upper contact and at all times immersed in the mercury fill, said cup being fixed with respect to the switch envelope and means for preventing the passage of a substantial current through the restricted mercury orifice.

17. In a mercury switch, a switch envelope, a mercury fill, means for shifting the level of the mercury fill, electrodes having spaced contacts at different heights within the envelope, a cup associated with said contacts having a restricted mercury orifice below the level of the upper contact and at all times immersed in the mercury fill, said cup being fixed with respect to the switch envelope and means for preventing the passage of a substantial current through the restricted mercury orifice, said means comprising telescoping the cup over said contacts.

18. In a mercury switch, a switch envelope, a mercury fill, means for shifting the level of the mercury fill, electrodes having contacts at different heights within the envelope, a cup telescoped over said contacts and having a restricted mercury orifice below the level of the upper contact at all times immersed in the mercury fill, one of said electrodes having contacts within and without said cup in order to prevent the passage of a substantial current through the restricted mercury orifice.
